INFANT'S CRIB

Earl F. Hamilton, Columbus, Ind., assignor to Hamilton
Cosco, Inc., Columbus, Ind., a corporation of Indiana

Filed Jan. 13, 1960, Ser. No. 59,032

Term of patent 14 years

(Cl. D5—5)

Fig. 2

FIG. 1 is a perspective view of an infant's crib embodying my new design and showing one side wall in erected position and the other side wall in collapsed position; and

FIG. 2 is a perspective view of the crib shown in FIG. 1, but showing the opposite end and side wall in a forwardly presented position, and showing both side walls in erected position.

I claim:

The ornamental design for an infant's crib, as shown and described.
